(57) CLAIM

The ornamental design for a computing device display screen with computer generated icon, as shown and described.

DESCRIPTION

FIG. 1 is a front view of a computing device display screen with computer generated icon, under an embodiment; and, FIG. 2 is an enlarged view of FIG. 1.

The broken lines showing a portion of the display screen of a computing device and unclaimed text, icons, and indicia form no part of the claimed design.

1 Claim, 2 Drawing Sheets

FIG. 1

FIG. 2
